UNITED STATES PATENT OFFICE.

R. SHERMAN MOORE, OF CINCINNATI, OHIO.

BELT-FASTENING MACHINE.

Application filed April 18, 1922. Serial No. 554,506.

To all whom it may concern:

Be it known that I, R. SHERMAN MOORE, a citizen of the United States, residing at Cincinnati, in the county of Hamilton and 5 State of Ohio, have invented certain new and useful Improvements in Belt-Fastening Machines, of which the following is a specification.

My invention relates to devices for applying fasteners to the ends of belts used for transmission of power. Its object is to apply the fasteners quickly and easily, by simple mechanism, to belts of different thicknesses as well as of different widths. Other 15 objects will appear in the course of the ensuing description.

I attain these objects by the device illustrated, for example, in the accompanying drawing, in which—

20 Figure 1 is a plan view of the device, opened for reception of the fasteners and the belt;

Fig. 2 is a side elevation of the same, the position of the belt operated upon being indicated by dotted lines, and parts of the machine also having their closed or pressing positions indicated by dotted lines;

Fig. 3 is a front elevation of the same, in closed or pressing condition;

30 Fig. 4 is a partial side elevation of the rear part of the machine, showing the positions of the rear operating parts when the machine is in closed or pressing condition; and

Fig. 5 is a detail perspective view of the 35 toggle links for one side of the machine, showing their relation when the machine is in open condition as in Figs. 1 and 2, more clearly than in those views.

40 As herein illustrated, the machine comprises a rear yoke 1 having the middle pedestal 2 with the struts 3 and 4 at front and rear ends, respectively, projecting to right and left from its bottom. Side plates 5 are secured to these struts 3 and 4 by bolts 6; and these plates 5 project forward from this yoke 1 and are tied together near their front ends, at the bottom, by a strut-rod 7, reduced at its ends to go through the plates 5 and receiving nuts on its outer ends clamping the plates 5. The upper edges of the plates 5 form ears 8 above the front struts 3 of the yoke 1; these edges sloping to the rear and front ends of the plates from these ears.

55 The bearing bar 9 extends across between

the ears 8, reduced at its ends to go through the ears and receiving nuts 10 on the ends, clamping the ears 8 and thus acting as a strut at the top like the strut-rod 7 at the bottom. Thus a rigid frame is made up.

Where the reduced ends of the bar 9 go through the ears 8 they are flattened at 9' to prevent turning of the bar 9; and this bar is square in its middle part to receive the clip-holder supports 11 secured to the bearing bar 9 about half way in toward the middle from respective sides of the frame, with their forward ends vertical and having T-slots 12 transversely through them, opening out through the forward ends. Preferably, 70 these supports 11 are made in upper and lower halves to facilitate cutting the T-slots 12; and these halves have rear flanges over and under the square part of the bar 9, secured thereto by bolts 13 through the bar 75 and flanges.

At respective sides of the frame, spaced in from the side plates 5, the lower levers 14 have ears 15 upwardly projected and embracing round parts of the bearing bar 9 80 to turn thereon. The upper levers 16 similarly have ears 17 projected down and embracing these round parts of this bearing bar 9, between the respective lower lever ears 15 and the adjacent side plates 5. Each lever has a front arm projecting forward from its fulcrum, and a rear arm projecting backward therefrom. The rear arms 18 of the lower levers 14 bend outward and the rear arms 19 of the upper levers 16 bend inward shortly to the rear of the bar 9 or fulcrum, bringing these rear arms 18 and 19 in the same vertical plane.

The yoke 1 is made with two parallel ribs 1' extending forward from the pedestal 2 95 to the front strut 3, and down from the pedestal 2 to the rear strut 4, and connected by these struts at their ends; and on top of the pedestal 2, aligned with these ribs 1' are the two bearing heads 20 with caps 21 with a clear space between them. The crank-shaft 22 has the lever head 23 at its middle and the two-arm cranks 24 at its ends, this head and these cranks preferably being integral with the shaft, which is journaled in the bearing heads 20, under the caps 21, held down by screws 25. The lever-head 23 occupies the space between the heads 20, and the cranks 24 lie immediately outside the respective heads. As here shown, the two 100

arms of each crank 24 extend at an angle of 120°, and the cranks are alined with each other. Each crank arm has an opening near its end. The lever-head 23 extends al- 5 most vertically downward when the crank arms remote therefrom are extending vertically upward, and has a tapered opening receiving the tapered shank of the handle- lever 26, held in the head 23 by a nut 27 on 10 a threaded extension of the lever; so that the lever 26 extends backward and upward when the parts are in the described position, as seen in Fig. 2.

The rear end parts of the lever arms 18 15 and 19 have transverse openings like the crank arms; those of the lower arms 18 receiving pivot lugs of respective toggle links 28, which links also have pivot lugs in the openings of the respective crank arms that 20 extend upward as above described. These links 28 lie inward from the arms 18, and have small offsets 29 spacing their main parts in from the arms 18. Toggle links 30 have pivot lugs in the openings of 25 the upper lever arms 19, and also have pivot lugs in the openings of the other arms of the respective cranks 24. These other links 30 curve over the links 28, with webs 31 connecting the legs of the curves, 30 for strength; these webs occupying the spaces left by spacing the links 28 inward as just described. This allows the crank element 24 to draw the arms 18 and 19 very 35 close together without interference of the links 28 and 30 with each other, although these links move in the same vertical plane.

Thus, a very compact construction is had, 40 with a long range of action for the toggle device. This relation of the links is clearly shown in Figs. 2 and 5; the latter view showing the inner sides of the links used at the left, or as seen in the upper part of the plan view in Fig. 1. The positions of parts just described are those for the open machine, with the front lever arms 32 and 33 of the lower and upper levers 14 and 16, 45 respectively, widely separated. As here shown, rotation of the crank-shaft 22 through 150° brings these front arms 32 and 33 nearest together, by separating the rear arms 18 and 19 to their greatest extent, with the links 28 and 30 radial to the shaft.

The lower jaw 34 is a rectangular bar gained on its bottom to fit on the arms 32 50 with shoulders against the inner sides of the arms; being held to the arms by screws 35 through the arms into the jaw. The upper jaw 36 is a similar rectangular bar, but gained on its front edge, up and down, with 55 the reduced end parts sliding snugly in recesses opening down through the lower sides of the respective upper arms 33. The upper end of each recess is beveled downward and outward toward the respective side of the machine. The shoulders 37 thus formed by

the gains across the front of the upper jaw 36 fit slidingly against the inner sides of the arms 33. Pins 38 project out from the ends of the jaw 36, outside the arms 33; and spring-prongs 39, fastened on the rear out- 70 sides of the levers 16, project forward under these pins 38, yieldingly holding the jaw 36 up in the arms 33.

Mounted on top of the jaw 36 are blocks 40 with straight inner ends 41 and outwardly and downwardly inclined tops, forming wedges 42 projecting out into the respective recesses, between the arms 33 and the jaw 36, with the tapered or inclined tops up against the beveled tops of the recesses. 75 These blocks 40 have small inverted U-shaped saddles over their inner end parts, with cheeks 43 projecting down along the front and rear sides of the jaw, to guide the wedges 42 in their inward or outward movement. On the top of the jaw 36, at its middle part, the turning-head or knob 44 is journaled on an upright screw 45 in the jaw top, and has opposite crank-pin recesses in its bottom. Links 46 have pins 47 projecting up into these recesses; these links lying under the head or knob 44 and projecting out in opposite directions to connect with respective ones of the blocks 40 by pins 48 projecting up into recesses in the bottoms 80 of the inner end parts 41 of the blocks, which bottoms are cut away or gained to receive these links thereunder (Fig. 3). As shown (Fig. 1), the links are so arranged that turning the knob or head 44 to the right forces the wedges 42 outward; which thus force the jaw 36 downward in the lever arms 33, toward the lower jaw 34, against the pressure of the spring-prongs 39. The taper of the 85 wedges 42 is very low, so that they remain in their outward adjustments by friction, not requiring any fastening for the knob or head 44 to prevent its turning. However, such fastening may be provided with 90 departing from my invention.

The belt-support 49 is a transverse bar with downward extensions at its ends; these extensions 50 embracing the strut-rod 7 close to the inner sides of the plates 5 and allowing the support 49 to be swung forward and downward, or upward until the top of the support is a short distance below the horizontal center line of the fulcrum of the levers 14 and 16 on the bar 9. Fixed to each adjacent side plate 5, on its inner side, is a spring plate 51, with an offset so that it extends along the inner side of the belt-support extension 50; the latter having a recess, and the plate 51 having a detent 52 springing into this recess as the support is brought to upright position. The near edge of the extension 50 is beveled at 53, so that the end of the spring-plate 51 rides onto the inner side of the extension during 95 100 105 110 115 120 125 130

the approach. Thus the support is automatically fastened in position; but may easily be unfastened for swinging forward and downward, out of the way when the 5 clip-holder 54 is to be inserted in the supports 11.

This clip-holder preferably is substantially as disclosed and claimed in my co-pending application Serial No. 479,679, filed June 22, 1921, in having a series of notches particularly adapted for holding wire clips such as my clip therein shown. 10 However, any suitable holder for any desired clips may be employed, when equipped 15 to be held in the supports 11. As here shown, the holder 54 has upwardly and downwardly projected flanges 55 at its back, and is slipped endwise into the T-slots 12 with the flanges 55 in the upper and lower 20 members of the slots, respectively, and the notches 56 of the holder 54 opening forwardly to receive the clips 57 similar to those above mentioned. These clips 57 are held in the holder by a long slender pin 58 25 passing transversely through the teeth of the holder, across the intervening notches, and the upper and lower members of the clips diverge forward above and below the belt end 59 slipped therebetween while supported on the support 49 (Fig. 2), and 30 stopped against the front edges of the clip-holder teeth; so that when the jaws 34 and 36 come together the clips 57 will be closed and their prongs will be pressed through 35 the belt and clinched therein. To permit some adjustment of the clip-holder 54 up and down when the jaws 34 and 36 close on the clips and belt, the T-slot parts are made 40 slightly wider up and down than the holder flanges 55, and the front opening of the slot also is slightly wider than the body of the holder up and down; but preferably the flanges 55 have a snug sliding fit in the T-slot parts to keep the holder 54 from tilt- 45 ing.

About midway from front to rear of the pedestal 2 a post 60 is formed thereon, with a vertical guide slot 61 in its rear side; the pedestal 2 being open at the bottom from 50 this post 60 backward. This slot 61 is adapted to form a guide for a rack 62, shown by dotted lines in Figs. 1 and 2, with teeth facing backward and in mesh with teeth of a pinion 63, only part of which is 55 indicated, by dotted lines. This pinion is fixed on the crank-shaft 22 in place of the lever-head 23 and lever 26 to make the machine foot-operated or power-operated, accordingly as a treadle or suitable power motive apparatus is operatively connected to 60 the rack 62, preferably below the machine; neither of these devices being illustrated herein. The top of this post 60 is the forward stop for the lever 26.

65 A gang of clips 57, in the holder 54, being

mounted in the T-slot of the holder 11, the belt support 49 being swung forward and downward to afford free access for this placing of the clips by insertion of the holder 54 endwise from either side of the machine 70 into the T-slot, the belt-support 49 then is swung up and latched in place by the spring plate 51 as before mentioned. The end of the belt 59 then is placed on the support 49 with its end between the upper and lower 75 clip members and back squarely against the front of the clip-holder 54. During these operations the handle-lever 26 is swung farthest back as seen in Figs. 1 and 2, holding the jaws 34 and 36 wide apart. Then 80 the handle-lever 26 is pulled forward, closing the jaws and effecting the fastening of the clips 57 in the belt. Now the greatest pressure, for a given pressure at the handle of the lever 26, is exerted by the jaws 34 and 36 when the pivotal connections of the toggle-links 28 and 30 to their respective crank arms and levers are in radial alinement relatively to the center of the crank-shaft 22, as seen in Fig. 4; and thus it is 85 highly desirable that the end of the clip closing and fastening operation coincide with this alinement of these links. By making one of the jaws, as the upper jaw 36, 90 adjustable toward and away from the other jaw, as by the wedges 42, any belt of any thickness within the range of the machine may have the closing operation completed on it with this coincidence, as well as with the faces of the jaws 34 and 36 parallel and 95 normal to the opposite parallel surfaces of the belt. This is provided for, preferably, by inserting the belt and closing and adjusting the jaws thereto before the clips are inserted in their position with their holder. 100 Then the jaws are opened, the clips inserted in their holder, and the jaws closed thereon with the adjustment given to them by the wedges 42. But this adjustment can be given at any stage, so as to insure a combination of the two important advantages 105 of parallelism of the jaw faces and alinement of the links radially.

Modifications other than those instanced herein may occur, and therefore, while certain constructional details are deemed preferable in connection with my invention, and I have shown and described these rather specifically in elucidating the construction and use of my invention, as is required, I 115 do not wish to be understood as being limited to such precise showing and description, but having thus fully described my invention, what I claim as new and desire to secure by Letters Patent is:

1. In a belt-fastening machine, a pair of jaws having faces of substantial longitudinal and transverse dimensions, means for positioning belt fasteners between said jaws, one jaw mounted to swing toward the other, 130

operating means to swing said jaw, and a wedge for moving said jaw rectilinearly to variously space said jaws with both dimensions in parallel relation coincident with 5 the maximum closing exertion of said operating means on said jaw.

2. In a belt-fastening machine, a pair of fulcrumed elements, jaws mounted on the respective elements to swing toward each other with said elements, a crank element, links connecting the respective fulcrumed elements to circumferentially remote parts of said crank element, to bring said jaws toward each other by rotation of said crank 10 element until said links are radial to said crank element, and means for moving one jaw on its fulcrumed element to variously space said jaws in parallel relation coincident with said radial relation of said links. 15
3. In a belt-fastening machine, a pair of jaws, a pair of arms, one of said jaws being slidably mounted on said pair of arms, wedges entering between said jaw and the respective arms, rotary operating means on 20 said jaw, and links connecting circumferentially remote parts of said operating means and said wedges.

4. In a belt-fastening machine, a pair of jaws, a pair of arms, one of said jaws being slidably mounted on said pair of arms, wedges entering between said jaw and the respective arms, and means for moving said wedges in opposite directions in unison. 30

5. In a belt-fastening machine, a pair of jaws, a pair of arms, one of said jaws being slidably mounted on said pair of arms, wedges entering between said jaw and the respective arms, rotary means on said jaw, links connecting circumferentially remote 35 parts of said rotary means and said wedges, and yielding means holding said jaw toward said wedges.

6. In a belt-fastening machine, a pair of jaws, a bar on which one jaw is mounted to swing toward the other jaw, a holder support fixed on said bar and having a T-slot opening out between said jaws, and a 40

clip-holder having flanges engaging in said T-slot.

7. In a belt-fastening machine, a pair of 50 fulcrumed elements, jaws mounted on the respective elements, a crank element and a lever-head integrally connected, a lever fixed in said head, and links connecting the respective fulcrumed elements to circumferentially remote parts of said crank element, to bring said jaws toward each other by rotation of said crank element due to movement of said lever. 55

8. In a belt-fastening machine, a pair of 60 fulcrumed elements, jaws mounted on the respective elements, a crank element, and links connecting the respective fulcrumed elements to circumferentially remote parts of said crank element to bring said jaws 65 toward each other by rotation of said crank element, one of said links being curved around the other link.

9. In a belt-fastening machine, a pair of 70 fulcrumed elements, jaws mounted on the respective elements, a crank element, and links connecting the respective fulcrumed elements to circumferentially remote parts of said crank element to bring said jaws toward each other by rotation of said crank 75 element, one of said links being curved around the other link and having a web connecting the members of the curve, and the other link being offset to pass along side said web. 80

10. In a belt-fastening machine, a pair of fulcrumed elements, jaws mounted on the respective elements, a crank element, links connecting the respective fulcrumed elements to circumferentially remote parts of 85 said crank element, to bring said jaws toward each other by rotation of said crank element, a lever connected to said crank element, a stop for said lever, and a guide on said stop for a rack to mesh with a pinion 90 fixed to said crank element in place of said lever.

R. SHERMAN MOORE.
